DESIGN FOR A BOOK END OR SIMILAR ARTICLE

Louis V. Aronson, Newark, N. J., assignor to Art
Metal Works, Inc., Newark, N. J., a corporation
of New Jersey

Application May 16, 1936, Serial No. 62,674

Term of patent 3½ years

To all whom it may concern:

Be it known that I, Louis V. Aronson, a citizen
of the United States, residing at Newark, in the
county of Essex and State of New Jersey, have
invented a new, original, and ornamental Design
for a Book End or Similar Article, of which the
following is a specification, reference being had
to the accompanying drawing, forming part
thereof.

Fig. 1 is a front elevation, and
Figs. 2 and 3 are opposite side elevations of the
article showing my new design.

I claim:

The ornamental design for a book end or simi-
lar article, substantially as shown.

LOUIS V. ARONSON.
